UNITED STATES PATENT OFFICE.

THOMAS HENRY COOPER, OF TORONTO, CANADA, ASSIGNOR TO THE
TORONTO GRAIN AND SEED CLEANER AND GRADER MANUFAC-
TURING COMPANY, LIMITED, OF SAME PLACE.

GRAIN CLEANER AND SEPARATOR.

SPECIFICATION forming part of Letters Patent No. 648,485, dated May 1, 1900.

Application filed February 11, 1899. Serial No. 705,309. (No model.)

To all whom it may concern:

Be it known that I, THOMAS HENRY COOPER, manufacturer, of the city of Toronto, in the county of York, in the Province of Ontario, 5 Canada, have invented certain new and useful Improvements in Grain Cleaners and Separators, of which the following is a specification.

My invention relates to improvements in grain cleaners and separators; and the objects of the invention are, first, to devise a simple means to adjust the size of the orifice at the bottom of the feed-hopper; secondly, to provide a simple means whereby the grain 15 may be fed evenly through the orifice of the feed-hopper; thirdly, to devise an improved construction of hopper under the feed-hopper screen, whereby all seeds may be removed from the grain and carried out of the machine 20 before such grain can reach the riddles, which are subjected to the action of the blast from the fan; fourthly, to provide a simple means whereby the oats, chaff, and other foreign matter may be expeditiously carried out to 25 the outer end of the riddle, so as to enable the blast from the fan to act with the greatest effect to remove such matter from the grain; fifthly, to so construct the fan-chest that the 30 riddles only and at the same time provide for the conveyance of the grain to the outer ends of the screens and lower shoes, so that such grain may be screened to the best advantage; sixthly, to provide an improved adjustable form of tail-board by which the grain 35 or refuse may be impeded in its course or directed into or out of the machine as required; seventhly, to provide an improved combined form of shake and agitator for the lower shoe and screen, so as to prevent such screen choking with small foreign matter or particles lodging in the mesh of the screen; eighthly, to provide an improved means whereby the shoes may be shaken and the upper 40 shoe given any desired length of movement, and, ninthly, to provide a simple means whereby cockle, tares, and other foreign refuse matter that have not been removed by the wind-blast from the uppermost screen of the 45 lower shoe may be effectually removed before 50

the grain passes out of the machine; and it consists in the arrangement and construction of my machine, as hereinafter more particularly explained, and pointed out in the detail.

Figure 1 is a perspective view of a grain 55 cleaning and separating machine constructed in accordance with my invention. Fig. 2 is a longitudinal section through the machine. Fig. 3 is an enlarged detail showing the means for giving a longitudinal movement to the 60 grain-distributing mechanism for the feed-hopper. Fig. 4 is a detail showing the means for imparting movement to the fan and shoes.

In the drawings like letters of reference indicate corresponding parts in each figure. 65

A is the frame of the machine.

A' represents the side boards of the upper hopper, which are stationary.

B B' are the inclined bottom boards.

C is the adjustable bottom board, which is 70 supported in suitable guideways. The inclined bottom boards B B' are separated in the center, so as to leave a longitudinal orifice a, and it is with the object of adjusting the size of this orifice in order to feed the 75 grain more or less quickly that the adjustable board C is provided. In order to adjust this board, I provide a rack D, which is suitably secured to the end of the board C and has a quadrant E, which engages therewith. The 80 quadrant E is provided with a handle e. A spring-rod e' extends through the quadrant and is suitably supported in the side boards A'. The spring-rod e' at the center fits into a notch e² in the bracket E', which is secured 85 to the bottom of the end board C'. It will thus be seen that the normal tendency of the spring-rod e', which forms the axle upon which the quadrant turns, is to keep such quadrant into close mesh with the rack D. 90

In order to adjust the size of the orifice a, it is merely necessary for the attendant of the machine to grasp the handle e and swing the quadrant E, whereupon the board C may be adjusted into any position desired and 95 will remain in such position.

In order to feed the grain evenly through the orifice a, I provide a cross-bar F, supported in suitable brackets f and provided with upwardly-extending loops f', which are 100

located in close proximity to the lower edge of the inclined end board B of the hopper. On one end of the bar F, I provide a bracket f^2 .

B² is a cross-bar which extends across beneath the bottom board B.

G is the upper shoe, which is provided with side boards G'.

g is a cross-board forming part of the shoe G and extending between the side boards G'.
10 g' is a cross-bar, also extending between the side boards G'.

H is a bell-crank which is pivotally connected to the pin-shaped end of the bracket f^2 at one end and is pivoted on the bracket 15 h, attached to the bottom of the cross-bar B².

The opposite end of the bell-crank is pivotally connected to the pin i, forming part of the bracket I, secured to the top of the cross-bar g'. It will be seen that as the shoe G derives a longitudinal movement in the manner hereinafter described a corresponding crosswise movement will be imparted by the crank H to the bar F and consequently the loops f', thereby serving to distribute the 25 grain as it passes through the orifice of the hopper.

J is the uppermost screen, which is supported on the cross-bars g² and g³, extending between the side boards of the shoe G. K is 30 a curvulate metal hopper, also supported upon the cross-bars g² and g³ and inclined from one side to the other, as indicated by the full and dotted lines in Fig. 2. At one side of the shoe, and necessarily at the lower 35 side of the incline, is formed a spout J', which extends downwardly and outwardly, as indicated, thereby serving to convey all seeds from the grain before such grain reaches the riddles L, L', and L², where it is 40 subjected to the action of the wind-blast.

M is the fan-casing, which is for the most part cylindrical in form and is suitably supported on the frame of the machine. The bottom, however, of the casing is inclined at 45 M'. The casing M is so constructed as to leave an orifice m at the forward end of the machine, which is bounded at its upper and lower ends by the inclined boards M² and M³, which necessarily direct the course of the 50 blast upwardly toward the riddles L, L', and L². M⁴ is an inclined board extending from the upper end of the board M³ forwardly to the bottom edge of the side board G' of the shoe. All these boards extend from side 55 board to side board of the shoe G. The riddles L, L', and L² are supported at the inner end upon the cross-bars g⁴ and pins g⁵ and g⁶, respectively, and at the outer end by suitable pins extending into the side racks g⁷, which 60 it is not necessary here to describe, as it forms no part of my invention.

N is an apron, which is secured at the inner end on a bar n, which is placed to abut the outer end of the screen J. The apron N 65 extends outwardly over the upper riddle L and may be made of canvas, oil-cloth, or any other suitable material, its object being to

carry the oats, chess, and foreign matter far out onto the riddle, so as to enable the blast from the fan, hereinafter described, to remove such foreign matter from the grain. 70

O is the fan, which is formed in any usual manner with blades o and supported on a central shaft o', which is journaled at the ends in suitable bearings o². On the end of the shaft 75 o' is secured a sprocket-pinion o³, which is connected by a sprocket-chain o⁴ to a sprocket-wheel P, journaled on a suitable stud on the frame and provided with a crank-handle p. By this crank-handle it will therefore be seen 80 that the necessary movement is imparted to the fan O and to the shoes, as will hereinafter appear.

o⁵ is a pin extending eccentrically from the sprocket-pinion o³ and provided with a friction-roller o⁶. The friction-roller is located in the slot q of the bar Q and has washers o⁷ at each side to prevent it being longitudinally displaced. The lower end of the bar Q is pivoted at q' on the frame and is pivotally connected intermediate of its length to the pin-shaped end of the bracket q², which is secured to the side of the lower shoe R. The opposite side of the machine is provided with a similar bar Q, and consequently this end of 95 the shoe R is supported upon the bar Q by means of the brackets q². The opposite end of the shoe is supported by the bell-crank-shaped hangers r, which are pivotally connected to the frame by the bolt r' and to the 100 shoe by the bolt r². A rod r³ extends through the free end of the bell-crank-shaped hangers and through a slot r⁴ in the side of the shoe. The rod r³ extends directly across underneath 105 the upper screen R' of the shoe.

R² is the lower screen of the shoe, and R³ is the exit-spout for the lower screen, which is inclined and extends outwardly from the side of the machine, and R⁴ is the exit-spout for the upper screen, which extends out from 110 the end of the machine on the same incline as the screen. The shoe R, it will be seen from the description hereinbefore referred to, derives, by means of the eccentric roller extending into the slotted end of the bar Q at 115 each side of the machine, a longitudinal vibratory movement, being supported by the bar Q and hangers r. As this movement is imparted it will be seen that the rod r³ will be tilted upwardly underneath the screen R', 120 so as to strike it continuously, and thereby thoroughly agitate it at the same time that the shoe is getting its vibratory movement, and thus effectually prevent such screen from 125 choking with foreign matter or particles lodging in the mesh.

At the front end of the board M⁴, I attach an apron m', made of canvas or other suitable light material, which lies upon the screen R' of the lower shoe for the major portion of its 130 length. This light apron has the effect of retarding the passage of the grain to the spout R⁴ until all cockle, tares, and other foreign matter are completely removed therefrom.

The bottom of the screen is provided with a suitable plate R⁵.

It will be noticed from the construction of my fan-chest that the blast is directed upwardly underneath the riddles, thereby operating with the greatest efficiency upon the grain and screening it thoroughly.

Primarily it is necessary to confine the grain so as to direct it to the upper screen of the lower shoe, and for this purpose I provide a tail-board S, having confining metal straps s, forming slots at the bottom thereof and through which extends the cross-rod S'. In the position shown in the drawings the tail-board is shown inclined, so as to leave an orifice m² above the screen and between it and the board M⁴, through which the grain is directed upon the screen. This tail-board, on account of its peculiar connection by the metal straps s to the rod, which serve to limit the movement thereof without detaching from the machine, can readily be swung around into different positions, this of course depending upon the class of grain that is being passed through the riddles and as to whether it is desired to blow it out from the machine or impede its progress.

Q is the upper shaker-bar, which is bent intermediate of its length and pivotally connected at q³ intermediate of its length to the frame of the machine. The upper end is provided with a slot q⁴, through which extends a pin q⁵, which is held in a metal strap T, having the elongated slotted ends t, through which pass the bolts t' into the block t², which is fastened to the shoe. The upper shoe is supported at each side by the hangers U, pivotally connected to the frame and the shoe, as indicated.

It will be seen that by adjusting the metal strap T and pin q⁵ therein in relation to the slot in the bar Q', the length of movement of the upper shoe may be varied as may be required for different sorts of grain, which is an important desideratum. The lower end of the bar Q' is bent at q⁶ and extends through a slot in the upper end of the bar Q, and consequently the movement that is imparted to the bar throws the lower shoe R in one direction and serves, on account of the peculiar pivoting of the bars Q and Q', to throw the upper shoe G in the opposite direction simultaneously.

It will thus be seen from this description that I have provided various improvements in the construction of grain cleaners and sepa-

arators, which I find from practice has effectually overcome all defects of construction heretofore experienced in this class of machines.

Although I show the vibratory bars at one side of the machine with their accompanying mechanism and hangers for supporting and vibrating the shoes, it will of course be understood that duplicates of these parts are provided on the opposite side of the machine for the support of the shoes on that side.

What I claim as my invention is—

1. In combination in a grain-cleaning machine, the hopper having a synclinal bottom formed of two parts with a space between the adjacent edges thereof, a closing-board for said space guided in the sides of the hopper, a rack carried by said board, a spring-rod extending across the machine-frame beneath said rack and a quadrant journaled centrally on said rod and adapted to be held thereby in close contact with said rack, substantially as described.

2. In a grain cleaner and separator, the combination with the frame, the lower shoe and screens suitably mounted in said shoe, of the lower supporting and vibratory bars pivoted to the bottom of the frame, means for actuating said bars, brackets pivotally connecting the bars to each side of said shoe, bell-crank hangers pivotally connected to the frame and to the higher end of the shoe, and a rod connecting the free end of the bell-cranks and extending through slots in the side of the shoe underneath the upper screen, substantially as described.

3. In a grain cleaner and separator, the combination with the frame, the fan and fan-shafts, and shoes and hangers for supporting the shoes, of the lower vibratory bars pivoted at their lower ends to the frame, said bars being slotted at their upper ends, means interposed between the same and the shaft for rocking said bars as the crank rotates the upper vibratory bars intermediately pivoted to the frame having projections at their lower end engaging the slots in the lower vibratory bars, the upper ends of the upper bars being slotted, straps adjustably connected to the upper shoes and pins extending from said straps engaging the slots in the upper bars, substantially as described.

THOMAS HENRY COOPER.
